UNITED STATES PATENT OFFICE.

ARTHUR WELLS ROBINSON, OF MONTREAL, QUEBEC, CANADA.

FLOATING DISCHARGE-PIPE FOR HYDRAULIC DREDGES.

1,143,321.

Specification of Letters Patent. Patented June 15, 1915.

Original application filed July 12, 1913, Serial No. 778,644. Divided and this application filed June 23, 1914.
Serial No. 846,789.

To all whom it may concern:

Be it known that I, ARTHUR WELLS ROBINSON, a citizen of the Dominion of Canada, and a resident of the city of Montreal, 5 in the county of Hochelaga, Province of Quebec, and Dominion of Canada, have invented certain new and useful Improvements in Floating Discharge-Pipes for Hydraulic Dredges, of which the following is 10 a specification.

This application is a division of the application filed by me on the 12th day of July, 1913, Serial No. 778,644.

In apparatus of the class stated as heretofore constructed, the discharge pipes have usually been of comparatively small size and have usually been used under conditions in which they were more or less sheltered against violent wave action and other destructive agencies; but in recent years the size and power of such apparatus have very greatly increased and the conditions under which submarine dredging is done are frequently such as to subject the apparatus to 25 the destructive effects of storms and heavy currents in exposed positions and it has been found that to meet the requirements of the later day systems, much larger, stronger and hence more sea-worthy floats and correspondingly increased discharge pipes are 30 required than have heretofore been used. Furthermore the connecting devices between the several floats constituting the discharge system and also the connecting devices between 35 the ends of the several discharge pipe sections carried by the floats as heretofore used have been demonstrated to be comparatively useless in view of the enormous strains that are exerted upon them by reason 40 of the conditions above referred to.

It is the object of this present invention, therefore, to provide a special construction of spherical or so-called ball and socket joint connecting the sections of the discharge pipe and to supply it with suitable packing and co-acting parts whereby a non-rigid connection is obtained and leakage prevented.

The drawings hereof illustrate one form 50 in which my invention may be embodied and I regard it as a useful form in as much as the parts are simple, durable in construction and efficient in operation.

Figure 1 illustrates a vertical sectional

view showing the ends of two adjoining discharge pipe sections embodying the invention; Fig. 2 illustrates an endwise vertical sectional view taken through the center of the packing and looking in the direction of the arrow, the steel band or follower for 55 the soft packing and the compressing rod therefor being shown in elevation.

In the drawings 12, 12, are the adjoining ends of two sections of the discharge pipe. 13 is a strong annular casting very securely 60 bolted to the left-hand discharge pipe as shown by bolts 14 and on its upper part is a raised portion 15 having a reinforcing rib 16 and recessed as at 17 so as to receive a coupling link 18 which is provided with an 65 eye on its end through which passes a coupling pin 19. The interior of the casting 13 at its outer part is tapered as shown at 20 so as to afford the socket for the ball 70 about to be described, which is on the opposed end of the adjoining tube. This socket is for a short distance made parallel-sided or truly cylindrical, as shown at 21, so as to permit longitudinal movement of 75 the ball within it without changing the relation of the parts and near the outer edge 80 of this socket there is cut a groove as shown, within which are contained the following packing devices, a soft packing ring 22, next to it a split metallic compression ring 85 23 and outside of it a compressing band or rod 24, which has an enlargement 25 (see Fig. 2) at one end, which engaging with the walls of the socket as shown holds that end 90 rigidly in place, the other end, after making a ring-like circuit, terminates in a threaded part 26 provided with nut and jam nut 27 and 28, so that when these nuts are turned 95 up, the draft upon the rod will cause the circle described by it to contract and since 100 this rod engages with and slips upon the surface of the split metallic ring or band 23, it is obvious that uniform and inward radial pressure will be brought to bear upon the soft packing 22, thus forcing it into 105 tight contact with the outer surface of the ball, which is about to be described. 29 is an inner lining, which I prefer to apply throughout the tube in their lower arc so as to take the wear.

Referring to the ball construction, which, as stated, is applied to the opposed end of the adjoining discharge pipe, it comprises

a strong annular casting 30 rigidly attached as by bolts or rivets 31 to the end of the tube. I prefer, in order to reduce weight, to core out a hollow space 32 in this casting, as shown 5 in Fig. 1. Its outer surface, which constitutes the ball of the ball and socket joint, is of course given such dimensions and contour, preferably truly spherical, as to enable it to properly co-act with the socket on 10 the opposed end of the adjoining tube. Immediately in rear of this ball is another strong casting 33, provided with an upwardly extending plate 34, through which there is an opening 35 for the passage of the 15 shank of the link 18, which has near its end a strong washer or abutment plate 36 and is provided with nut and set nut 37 and 38. A spring 39 encircles the shank of the link and takes a bearing against the outer surface 20 of the plate 34 and the inner surface of the washer or abutment plate 36. I prefer to employ duplex springs, one within the other, as shown, the smaller one 40 being of less power than the outer and larger one 25 39. I find this improves the cushioning effect.

The operation of the apparatus is as follows: The link and pin connection between the ends of adjoining discharge pipes being 30 superimposed over the center of the ball and socket joint, as clearly shown in Fig. 1, permits horizontal flexure to the full extent of the movement for which the joint is designed and this flexure is in a measure controlled and cushioned and the strains upon the link and pin connection are reduced by 35 the springs 39 and 40. Furthermore, slight longitudinal separation of the discharge pipes is permitted should strains be exerted 40 in that direction because of the parallel or truly cylindrical portions 21, 21 of the socket through which the ball can move to such degree as may be necessary, without, however, disorganizing the structure and 45 without materially occasioning leakage because the moment the parts are drawn together again by the action of the powerful spring or springs 39 and 40, then the packing of the ball will again effect water-tight, 50 or substantially water-tight connection between the ball and its socket. This construction likewise has the further important advantage that it permits vertical flexure as well as horizontal flexure to such extent as 55 will be necessary even in a rough seaway and that this movement may be permitted without any jamming of the parts, I ream out the eye in the coupling link 18 at top and bottom as shown in Fig. 2. If the packing 60 should at any time fail to make a satisfactorily tight joint between the ball and its socket, then by tightening up the nuts 27, 28, the packing throughout its entire circumference will be forced inwardly, thus 65 maintaining the desired tight fit.

The compressing rod or band 24 is a very simple, inexpensive and effective method of sealing a joint of the character here presented. It will be particularly noted that my improved construction is especially 70 valuable in ponderous apparatus of the class in question because owing to the size and weight of the floats and discharge pipes, they are seldom removed from the water after once being launched. Therefore access to their under parts is practically precluded and by my construction the coupling and uncoupling of the several floats is a very simple, inexpensive and expeditious operation because all the connecting parts are 75 above the water line and all that is necessary is to disengage the chains or equivalent devices (not shown) which always connect the floats, and lift the coupling pin 19, whereupon the several float units become 80 entirely detached from each other because the ball and socket construction is such that the ball may be drawn endwise out from the socket without any mechanical operation whatever. Also that the several floats and 85 the discharge pipes are held in requisite flexible connection with each other by the heavily constructed and strong ball and socket joint, which connects the interlocking ends of the discharge pipe sections and that 90 the cushioned link and pin connection, while some aid in this respect, fulfills the important office of holding the several float sections together and that it does this by a cushioned or slightly yielding action, thus enabling the 95 structure to twist vertically as is frequently 100 necessary in a seaway.

It will be obvious to those who are familiar with such matters that modifications may be made in the details of construction 105 and yet the essentials of the invention be retained. I therefore do not limit myself in this respect.

I claim—

1. In a floating discharge pipe for dredges, 110 a ball and socket joint in the discharge pipe, a link and pin connection superposed upon the upper side of the adjoining ends of the discharge pipe sections, the pin being substantially in the same vertical plane as the 115 center of the ball, and a packing for the ball and socket joint comprising an annular recess in the socket, an annular packing therein, a compression band outside of the packing, a split metallic ring interposed between the packing and the compression band, and means to tighten the band.

2. In a floating discharge pipe for dredges, 120 a ball and socket joint in the discharge pipe, the ball being a segment of a sphere and the 125 outer part of the socket cylindrical, a packing interposed between the ball and the socket comprising an annular recess in the socket, an annular packing therein, a compression band outside of the packing, a split

metallic ring between the packing and the compression band, and means to tighten the band, and a link and pin connection between the adjoining ends of the discharge pipe, 5 the pin being substantially in the same vertical plane as the center of the ball, and spring cushioning devices which permit longitudinal movement of the link.

In testimony whereof I have signed my name to this specification in the presence of 10 two subscribing witnesses.

ARTHUR WELLS ROBINSON.
